(57) **CLAIM**

The design for a cardboard tube plug, as shown and described.

DESCRIPTION

FIG. 1 is an isometric view of the cardboard tube plug embodying the present ornamental design;

FIG. 2 is a front view thereof;

FIG. 3 is a right side view thereof;

FIG. 4 is a left side view thereof;

FIG. 5 is a rear view thereof, showing the claimed cardboard tube plug in an upside down position;

FIG. 6 is a top plan view thereof; and,

FIG. 7 is a bottom plan view thereof.

The broken lines in FIG. 7 represent the three dimensional configuration of the four innermost circular surfaces, and form no part of the claimed design.
